UNITED STATES PATENT OFFICE.

WILLIAM B. PARK, OF LINTON, INDIANA, ASSIGNOR OF ONE-HALF TO CLYDE M. ZINK,
OF LINTON, INDIANA.

MOTOR CONTROLLER.

Application filed January 24, 1924. Serial No. 688,312.

This invention relates to electrical control devices, particularly to controllers for electric haulage motors and the like, and has for its object the provision of a novel finger bar and terminal arrangement possessing marked advantages over the usual construction.

It is well known that controller boxes of this general character embody two rotary cylinders having contact segments co-operating with contact fingers connected with the respective power supply lines and motor leads, one cylinder acting to regulate the speed of the motor and the other controlling the reverse. In the ordinary construction, the fingers are carried by a wooden bar to which they are rigidly bolted and have their terminals so mounted that the current must pass through the fingers themselves to the various motor leads. This construction is faulty in several respects. The principal object is that the current passing through the spring fingers causes excessive heating thereof, which in a comparatively short time, reduces and eventually destroys the temper so that the fingers lose their resilience and fail to make close contact with the segments. This condition causes arcing at the points of contact which naturally soon results in burning away the fingers and rendering them useless. Another disadvantage is that the finger bar, being wooden, does not possess the proper strength and durability so that eventually the bolts holding the fingers become loose and permit the fingers to move, thereby causing poor contact. The first mentioned objection is a serious one inasmuch as burning and tempering of the fingers necessitates entire replacement. The ordinary arrangement or construction is defective in other respects as is known to those skilled in the art.

It is with the above conditions in view that I have designed the present invention which contemplates the construction of the finger bar from or as a metal frame upon which the various fingers are detachably mounted and insulated, the frame being formed for the accommodation of the usual arc guards located between the successive fingers.

The essential feature is the location or disposition of the terminals upon the ends of

the fingers whereby the current will pass directly to the contacts or ends without passing through the fingers themselves, this arrangement preventing heating and tempering of the fingers.

Another object is the provision of a finger construction in which the contact shoes or burning points are detachably mounted upon the free ends of the fingers so as to be capable of replacement when worn or burned, it being unnecessary to discard the entire finger itself, the shoes being moreover, held by screws passing downwardly through the finger.

Other objects and advantages such as simplicity in construction, ease of manufacture, accessibility for repairs and replacements, durability, economy and the general improvement of the art will become apparent during the course of the following description in conjunction with the drawings, in which—

Figure 1 is a view of a controller box embodying my invention, the cover of the box being removed and the arc guards being shown in section, the plane of the view being indicated by the line 1—1 in Figure 2,

Figure 2 is a section on the line 2—2 of Figure 1.

Figure 3 is a bottom plan view of the finger bar.

Figure 4 is a side elevation thereof.

Figure 5 is a diagram of the electric circuit.

Referring more particularly to the drawings the letter A represents a controller box within which are rotatably mounted the controller cylinders B and C operable in the usual manner and carrying the usual segments D and E respectively. The cylinder B controls the motor speed while the cylinder C controls the direction. The letter F represents a resistance tapped at several points and having its leads connected with contacts K, L, P and with a blow out coil G which is, in turn, connected with a pair of contacts U. One feed wire H connects with a contact V, while the other I connects with one terminal of the series field J of the motor. One terminal of the shunt field coils W is connected with the contact K. The contacts X and Z are connected with the

motor brushes. The remaining terminal of the series field is connected with a contact Y. The two fields are connected as shown at S. The contacts K, U, P, L and V cooperate with the segments D while the contacts X, U, Z and Y cooperate with the contact segments E. This wiring or mode of connection is conventional and no claim is made thereto, the matter being described and illustrated solely for the sake of clearness. For this reason a tracing out of the circuits is unnecessary as the action will be easily understood by one skilled in the art.

In carrying out the invention I provide a finger bar designated broadly by the numeral 10 and formed as an angular frame of metal, preferably iron having attaching feet 11 by means of which it may be properly mounted in the box A. This frame embodies a bar 12 having secured thereon an insulating covering 13 of any suitable material but preferably of mica. The edges of this covering extend downwardly as shown at 14 to cover the edges of the bar. At one edge the bar and insulating covering are notched or cut away as indicated at 15 for the accommodation of the arc guards 16 which are of ordinary construction. The frame further includes a partition bar or plate 17 spaced somewhat from the bar 12 and extending beneath the notches 15 to form a rest for the arc guards as clearly disclosed in Figure 2.

The fingers corresponding to the contact K, U, P, L, V, X, U, Z and Y are all carried by the frame 10. Each finger comprises a resilient or spring strip 18 disposed upon the insulating covering 13 and secured by suitable screws 19 which pass through an insulating block or strip 20 disposed upon the finger and which also pass through suitable insulating bushings 21 extending through holes in the finger and abutting against the covering 13. By this mounting it is evident that the fingers will be securely held upon the finger bar and at the same time effectually insulated therefrom and consequently from one another.

Carried by the free end of each finger is a relatively large and heavy contact shoe 22 having a curved face for coaction with the associated cylinder segment. Also carried by the free end of each finger, is a terminal connection comprising a socket member 23 and a plate like base 24. The terminal and shoe are both held upon the finger and in fixed relation to each other by suitable screws or the like 25 which pass through the base plate 24, through the finger and into the shoe. The sockets 23 are for the reception of the ends of the cables which are held therein by suitable set screws 26.

Two socket members 27 and 28 are here represented as being double or having two holes therein for connection of two cables

therewith, these socket members being carried by the fingers which correspond to the contacts U so that the necessary blow out coil connection may be made thereto. However there is no limitation whatever as to whether or not one or more sockets or terminals are made double or single.

In the use of the device it is obvious that the current passes directly through the contact shoes and terminal members without passing throughout the length of the fingers. In this way it will be apparent that heating, or at least excessive heating of the fingers and consequent detempering will be prevented. The great advantage of this feature is that the fingers will retain their proper resilience for an indefinite period and will not need to be replaced as is the case in the ordinary construction and arrangement. The action of my invention is the same as the action of the ordinary arrangement in so far as the controlling of the motor is concerned. It will be noted that the contact shoes are relatively heavy so as to be capable of prolonged use before becoming worn or burnt to such an extent as to necessitate replacement. Whenever it should occur that a contact shoe requires replacement, such may be accomplished without disturbing the mounting of the finger itself, the screws 25 being removed to effect removal of the shoe, a new shoe being placed in position and the screws replaced. If by chance it does become desirable to replace an entire finger, it is obvious that this may likewise be accomplished in an extremely simple manner by removing the screws 19 and placing the new finger in position without disturbing the mounting of the bar or any other parts of the mechanism.

Summing up it will be apparent that I have thus provided a very simple, easy and cheaply built finger bar and finger construction wherein maximum durability, efficiency, economy and accessibility will be assured with the minimum likelihood of derangement and expenditure of time and labor for making adjustments, repairs or replacements.

While I have shown and described the invention as involving a certain number of fingers and while the diagram represents the device as used in connection with direct current motors, it is obvious that the number of fingers may be increased or decreased depending upon the specific controller system and it is likewise evident that the arrangement may be varied for use in connection with alternating current motors. I reserve the right to make all these changes, modification or variations together with all others in the details of construction and arrangement provided there is no departure from the spirit of the invention or the scope of the subjoined claim.

I claim:

In a motor controller, a casing, drums mounted therein and carrying contacts, a finger bar formed as a metal frame located 5 between the drums, fingers mounted upon and insulated from the finger bar and co-operating with the respective drums, an

elongated support carried by the finger bar, the edge of the finger bar toward one drum being notched, and a plurality of arc guards ¹⁰ located within said notches and resting upon said support.

In testimony whereof I affix my signature.

WILLIAM B. PARK.
